CLAIM

The ornamental design for a display screen or portion thereof with graphical user interface, as shown and described.

DESCRIPTION

FIG. 1 is a first embodiment of a front view of a display screen or portion thereof with graphical user interface showing our new design.

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof; and,

FIG. 6 is a front view of a sixth embodiment thereof.

The long dash, short dash broken lines in the figures depict a display screen or portion thereof and form no part of the claimed design. The remaining short dash, short dash broken

(Continued)

lines depict portions of a graphical user interface and form no part of the claimed design.

1 Claim, 3 Drawing Sheets
